UNITED STATES PATENT OFFICE.

JOHN J. MONAGHAN, OF PROVIDENCE, RHODE ISLAND.

CURTAIN-ROD THREADER.

SPECIFICATION forming part of Letters Patent No. 758,845, dated May 3, 1904.

Application filed December 1, 1903. Serial No. 183,406. (No model.)

To all whom it may concern:

Be it known that I, JOHN J. MONAGHAN, a citizen of the United States, residing at the city of Providence, in the county of Providence and State of Rhode Island, have invented certain new and useful Improvements in Curtain-Rod Threaders, of which the following is a specification.

This invention relates to a device for attaching in one end of the telescoping rods which form the support for a sash-curtain; and the object of my invention is to provide means whereby the tubular rods can be readily passed through the hem of the sash-curtain when the same is to be mounted in position on the window-frame.

My invention consists, in combination with the tubular rod-support of a sash-curtain, of a curtain-rod threader comprising an oval-shaped head having two flaring arms projecting from one end thereof and adapted to hold by frictional contact on said rod-support in the manner as hereinafter described and claimed.

In the accompanying sheet of drawings, Figure 1 represents an elevation view of my threader for attachment to the rod-support of a sash-curtain. Fig. 2 is a central longitudinal sectional view showing the threader as applied to the rod-support, as before passing through the hem of the curtain. Fig. 3 illustrates the curtain in place upon its rod-support, as when ready to be mounted on the window-frame.

Like letters indicate like parts.

Referring to the drawings, A designates my threader as a whole comprising an oval-shaped head b, having two flaring arms c c projecting from one end thereof.

d' and d² are the usual tubular rods which telescope together and form the support from which the sash-curtain e is suspended.

The sash-curtain is provided with a stitched hem at its upper edge, as at f, to receive the rods d' and d².

When the curtain is to be mounted on the rods by my said threader, the arms c c are pressed together and inserted within the exposed end of the rod d' and forced inwardly until stopped by the head b, which has its central portion a trifle larger in diameter

than the exterior diameter of the rod d', as shown in Fig. 2. The arms c c are made of resilient material, so that when inserted in the rod they expand and hold the device in position by frictional contact on the rod. After 55 the threader has thus been attached to the rod-support the pointed end of the head b is made to enter the opening formed by the hem f in the curtain, and this head having its middle portion larger than the exterior diameter of 60 the rod d' will cause the hem to spread outwardly or free from the edge d, formed on the end of said rod, so that the both rods d' and d² can be quickly forced through the hem of the curtain, after which the threader A is 65 withdrawn from its position on the rod d'.

The rods d' and d² are provided with perforations g g to receive the usual screw-wires of the window-frame.

The common way of forcing the exposed 70 end of the rod-support in the hem of the curtain is necessarily slow, for the reason that the edge d, formed by the end of the rod, will contact with the surface of the hem and obstruct the passing of the rod therethrough 75 and frequently causes this portion of the curtain to become ragged or torn. I obviate this objectionable feature, as will be readily understood, as my attachable threader contains in itself all that is necessary to permit a 80 quick mounting of the sash-curtain upon its rod-support without in any way destroying the fabric of the curtain and at the same time a device that is simple in construction and inexpensive to manufacture.

Having described my invention, what I claim, and desire to secure by Letters Patent, is—

1. In a curtain-rod threader, the combination, with the tubular rod of a sash-curtain, 90 of an oval-shaped head whose central transverse portion is of greater diameter than that of the exterior diameter of said tubular rod, and said head having two integral flaring arms projecting together from one end thereof 95 and adapted to hold by frictional contact upon the interior surface of said tubular rod, substantially as set forth.

2. In combination with the tubular rod of a sash-curtain, the herein-described threader 100

A, comprising an oval-shaped head *b* having two arms *c*, *c* flaring from one end thereof, and said arms adapted to hold by frictional contact upon the interior surface of said tubular rod, substantially as shown and for the purpose specified.

In testimony whereof I have hereunto set my

hand in the presence of two subscribing witnesses.

JOHN J. MONAGHAN.
